Primary Examiner — Clare Ann Gannon

(57) **CLAIM**

The ornamental design for a curtain, as shown and described.

DESCRIPTION

FIG. 1 is a perspective view of a curtain, showing our new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged portion view taken from encircled portion labeled "FIG. 9" in FIG. 1;

FIG. 10 is an enlarged portion view taken from encircled portion labeled "FIG. 10" in FIG. 2; and,

FIG. 11 is an enlarged portion view taken from encircled portion labeled "FIG. 11" in FIG. 5.

The evenly broken lines where present illustrate portions of the curtain that form no part of the claimed design. The dashed-dot lines in FIGS. 1-2, 5 are for the purpose of depicting the boundary lines of the enlarged views and form no part of the claimed design.

1 Claim, 11 Drawing Sheets
